UNITED STATES PATENT OFFICE

159,138

CORN POPPER

Raymond C. Casanov, Chicago, Ill.

Application October 21, 1947, Serial No. 142,067

Term of patent 7 years

(Cl. D44—15)

To all whom it may concern:

Be it known that I, Raymond C. Casanov, a citizen of the United States and a resident of Chicago, in the county of Cook and State of Illinois, have invented a new, original, and ornamental Design for a Corn Popper, of which the following is a specification, reference being had to the accompanying drawing, forming a part thereof, and in which:

Fig. 1 is a side elevational view of a corn popper, showing my new design;

Fig. 2 is a top plan view of the same;

Fig. 3 is a bottom plan view of the same.

I claim:

The ornamental design for a corn popper, as shown.

RAYMOND C. CASANOV.
